METHOD OF AND APPARATUS FOR FLANGING CONTAINERS

Application filed February 20, 1929, Serial No. 341,531, and in Germany November 27, 1928.

My invention relates to a method of and apparatus for flanging containers, such as barrels, drums or the like, whereby a seat is provided for a cover plate or other closure means, and it is an object of the invention to provide a mechanism of this kind which is simple in construction, inexpensive to manufacture, and easy to operate. Other objects and advantages of the invention will be apparent from the following description and the features of novelty will be pointed out in the appended claims.

An embodiment of my invention is illustrated by way of example in the accompanying drawings in which Fig. 1 is a top plan view of the platform carrying the flanging rolls, illustrating the position assumed by the parts at the end of the flanging process proper; Fig. 2 is a section along line 2—2 of Fig. 1; Fig. 3 is a partial section along line 3—3 of Fig. 1; Fig. 4 is a partial top plan view of the platform, the clamping roll being removed; Fig. 5 illustrates in perspective view the complete machine; and Fig. 6 is a perspective view of the platform with its co-ordinated parts.

The pedestal 10 (Fig. 5) carries in its offset upper end a vertical shaft 11 provided with a pulley 12 and a disc 13 arranged to be driven from a suitable motor, not shown, by means of the belt 14. The disc 13 is provided with a shoulder 14' over which the upper edge of a container, such as a barrel or drum shell may be slipped to abut against the disc 13 to which the barrel or drum is then attached in any suitable manner, for instance, by clamping screws, not shown. The barrel or drum shell is thus held in position to be positively rotated about its longitudinal axis. The pedal 15 shown at the foot of the pedestal serves to operate a switch for the control of the motor which drives the pulley 12. While the barrel is being rotated, its lower edge is operated upon by the flanging tools which will be described hereinafter.

The pedestal 10 is provided with a vertical guide 16 to accommodate slidingly a carriage 17 in which a horizontal shaft 18 is journaled. This shaft carries a hand wheel 19 and a pinion 20 meshing with a rack 21

provided on the guide 16, so that by rotation of the hand wheel the carriage 17 may be raised or lowered, as desired. The carriage is integral with a sleeve 22 accommodating a vertical post 23 forming a support for the platform 24 upon which the guiding elements and the tools operating upon the lower edge of the barrel shell are mounted. The post 23 is preferably secured against displacement within the sleeve 22 by suitable means, not shown in the drawings.

The platform 24 with the parts mounted thereon is more clearly illustrated in Figs. 1, 2 and 6. It comprises a plate formed in its central part with a sleeve-shaped portion 25 which is slipped over the upper end of post 23 which is preferably of rectangular cross-section and abuts against a shoulder 26 on said post, and is kept in place by means of a washer 27 and a bolt 28. The platform 24 is provided with five radially disposed slots 29 serving to accommodate adjustable guiding devices designed to guide the lower edge of the revolving barrel shell which is clamped at its upper edge to the disc 13. Each of these guiding devices comprises a block 30 (Fig. 2) carrying a vertical pivot 31, preferably integral therewith, a horizontal pivot 32 mounted in the block and a lower section 33 of rectangular cross-section slidingly arranged within the slot 29. A clamping nut 34 screwed on a threaded projection 35 of portion 33 serves to keep the block 30 firmly in position. On pivot 31 a single guiding roll 36 is mounted while the pivot 32 carries two guiding rolls 37 and 38 capable of independent rotation. The rolls 36 and 37 serve to guide a revoluble ring 39 dimensioned to receive the barrel shell 40 (Fig. 2). The rolls 38 function as abutments for the lower rim of the barrel shell when the latter is introduced into the machine, while ring 39 serves to cooperate with a roll 41 to support the shell positively near the point at which it is worked upon by the flanging tools during the flanging operation.

The roll 41 is arranged in the plane and inside of ring 39 and is carried by a vertical pivot 42 depending from a bar 43. In order to permit the adjustment of the roll 41 to 100

rings 39 of different diameters corresponding to barrels of different size, the bar 43 is adjustably mounted on a carrier 44 by means of a pin and slot connection 45. Furthermore the carrier 44 is shiftable within predetermined limits so that a barrel shell clamped between roll 41 and ring 39 may easily be released for the purpose of removing the finished shell and inserting a new one. To this end the carrier 44, more clearly shown in Fig. 3, is pivotally mounted on a bolt 46 inserted in the platform 24 eccentrically of the barrel, and is provided with an outwardly extending arm 47 carrying at its end a sleeve 48 in which a spring-pressed block 49 having a handle 50 is mounted. The block 49 is arranged to engage alternatively one of two recesses 51 in the rim of platform 24 so that, when the block 49 has been withdrawn from its recess by means of the handle 50, the carrier 44 may be shifted and the pressure roll 41 may be withdrawn from its operative position to release the barrel shell 40.

The flanging tool proper is formed by a pair of rolls 52 and 53 having their upper faces arranged in close proximity to the lower face of ring 39 and spaced from the lower face of roll 41 by a distance equal to the thickness of the sheet metal to be operated upon. Each roll is provided with an axle 54 or 55 respectively, which is rotatably journaled within a rectangular block 56, or 57 respectively (Figs. 2 and 4). Nuts 58 serve to keep the axles in place. Both blocks are guided within a slot defined by arms 59 of the platform 24, and are provided with lateral flanges 60 bearing upon the finished faces of said arms. The radial slot defined by arms 59 extends in inward direction up to the sleeve-shaped portion 25 and is closed at its outer end by a cross-head 61 bolted to the end of the arms 59. This cross-head is provided with a central boring rotatably accommodating a sleeve 62 (Fig. 1) having attached and keyed to its outwardly projecting end a hand wheel 63. The sleeve is threaded and in engagement with a threaded spindle 64 which is rigidly attached to block 56, so that the latter by rotation of the hand wheel 63, may be positively displaced in the slot defined by the arms 59.

Block 56 is, furthermore, provided with two horizontal borings through which headed bolts 65 extend in inward direction to block 57 into which their ends are screwed (see Figs. 1 and 2). Each of these bolts is surrounded by a compressed spring 66 abutting, at the one side, against the heads of bolts 65 and, on the other side, against suitable shoulders provided within the borings of block 56. These springs tend to urge the blocks 56 and 57 toward each other so that the marginal portion of the barrel shell inserted between the rolls 52 and 53 is firmly clamped therebetween. The blocks are kept an adjustable distance from each other by adjustable abut-

ment screws 67. Furthermore, the inner block 57 is provided with a pin 69 (Fig. 1) cooperating with a stop member 70 which serves to limit the movement of the block. The member 70 is seated upon the one arm 59 and held in adjustable position by means of a bolt 71, and is formed with a recess within which the pin 69 is adapted to move.

The machine is operated in the following manner:

Preparatory to the flanging process proper, a ring 39 of suitable diameter corresponding to the diameter of the barrel shell is selected and inserted in the machine upon proper adjustment of the guiding blocks 30. The platform 24 is lowered by means of hand wheel 19, and the barrel shell is slipped over shoulder 14' to be attached to the rotatable disc 13. When this has been accomplished, the platform 24 is raised again until the lower end of the barrel shell enters ring 39, its entrance being facilitated by the inclined face of the ring until it abuts against the rolls 38. During this phase of the operation, the carrier 44 assumes the position in which the supporting roll 41 is withdrawn from the ring so that the lower end of the shell may readily be inserted, and the blocks 56 and 57 are so adjusted that the gap between the rolls 52 and 53 is in registry with the shell. When this has been done, the handle 50 is pulled out and the arm 47 is swung into the position shown in Fig. 1 in which the supporting roll 41 firmly bears upon the inside of the shell. To insure such a firm contact the bar 43 must be adjusted accordingly and, subsequently, be tightly clamped in place on its carrier 44 by means of a wedge 68 (Figs. 1 and 3).

The pedal 15 is then operated to start the revolution of the barrel shell and, when the same has acquired its full speed, the hand wheel 63 is turned to press block 56 gradually in an inward direction until it reaches the position shown in Fig. 2. In the course of the advance of block 56, the flange 72 is formed on the lower edge of the shell, while the marginal section 73 of the shell is tightly clamped between the rolls 52 and 53 owing to the action of the springs 65. The flanging operation is completed as soon as the pin 69 reaches its innermost position, illustrated in Figs. 1 and 4.

Upon completion of the flanging operation, the pedal 15 is released to stop the machine, handle 50 is pulled out and arm 47 is swung into its other position, in which the pressure roll 41 is withdrawn from ring 39 and from the freshly formed flange or shoulder 72 to permit the platform 24 to be lowered by means of the hand wheel 19. The barrel shell may then be released from the disc 13 and the next cycle initiated by turning the hand wheel 63 back until the pair of rolls 52 and 53 are so located as to permit the insertion of a new barrel shell.

It will be understood that while I have shown a particular embodiment of my invention, the latter is not limited to such embodiment. For instance, instead of bending the barrel edge inwardly, the same may be bent outwardly by causing the abutment member or roller 41 to engage the exterior face of the barrel while the position of the rollers 52 and 53 is reversed and the block 56 caused to be moved outwardly, so that pressure is exerted against the interior face of the barrel. It will also be recognized by those skilled in the art that the barrel may be supported at the bottom and the flanging 15 performed at the top, and that instead of being operated by a hand wheel 63, the spindle or screw 64 could be rotated by other means, such as a motor. It will also be clear that instead of moving the rollers 52 and 53 20 relatively to the barrel, the latter could be moved relatively to the rollers. Moreover, the barrel could be supported with its axis in a horizontal position, the flanging apparatus being suitable re-arranged. Other variations may be resorted to within the scope 25 of the appended claims without departing from the spirit of the invention.

I claim:

1. In an apparatus of the kind described, 30 the combination with a support, of mechanism for supporting a metal container, an abutment member adapted to engage one face of said container near one edge thereof, a movable pressure device for exerting pressure against the other face of said container from its edge to a point on the container adjacent to said abutment and situated between said edge and said abutment, means for producing relative rotation between said 35 container and said pressure device, and means for holding the portion of the container adjacent said edge parallel to the container axis.

2. In an apparatus of the kind described, 45 the combination with a support, of mechanism for supporting a metal container, an abutment member adapted to engage one face of said container near one end thereof, a movable pressure device for exerting pressure against the other face of said container from its edge to a point on the container adjacent to said abutment and situated between said edge and said abutment, means for rotating said container about its axis, 50 and a roller cooperating with said pressure device to hold the portion of the container adjacent to said edge parallel to the container axis.

3. In an apparatus of the kind described, 60 the combination with a support, of mechanism for supporting a metal container, an abutment member adapted to engage one face of said container near one edge thereof, a movable pressure device for exerting pressure against the other face of said container

from its edge to a point on the container adjacent to said abutment and situated between said edge and said abutment, means for rotating said container about its axis, means engageable with the container adjacent to its edge to hold the portion of such container adjacent to said edge parallel to the container axis, and a platform for supporting said pressure device, said platform being adjustable to accommodate containers of different 75 heights.

4. In an apparatus of the kind described, the combination with a support, of mechanism for supporting a metal container, means for rotating said container about its axis, a platform on said support, an abutment member mounted on said support and adapted to engage one face of said container near an edge thereof, a pressure device on said platform for exerting pressure against the other face of said container from its edge to a point on the container adjacent to said abutment member and situated between said edge and said abutment member, means for holding the portion of the container adjacent to said edge parallel to the container axis, and means for producing relative radial movement between said container and said pressure device.

5. In an apparatus of the kind described, 95 the combination with a support, of mechanism for supporting a metal container, means for rotating said container about its axis, a platform on said support, an abutment member mounted on said support and adapted to engage one face of said container near an edge thereof, a pressure device on said platform for exerting pressure against the other face of said container from its edge to a point on the container adjacent to said abutment member and situated between said edge and said abutment member, means for holding the portion of the container adjacent to 100 said edge parallel to the container axis, and means for producing relative radial movement between said container and said pressure device.

6. In an apparatus of the kind described, 105 the combination with a support, of mechanism for clamping a metal container to prevent longitudinal movement thereof, means for rotating said container about its axis, a platform on said support, an abutment member mounted on said platform and adapted to

engage one face of said container near one edge thereof, a pressure device for exerting pressure against the other face of said container from its edge to a point on the container adjacent to said abutment and situated between said edge and said abutment, means for holding the portion of the container adjacent to 110 said edge parallel to the container axis, and means for moving said pressure device radially with respect to said container.

7. In an apparatus of the kind described, 115 the combination with a support, of mechanism for clamping a metal container to prevent longitudinal movement thereof, means for rotating said container about its axis, a platform on said support, an abutment member mounted on said platform and adapted to engage one face of said container near one edge thereof, a pressure device for exerting pressure against the other face of said container from its edge to a point on the container adjacent to said abutment and situated between said edge and said abutment, means for holding the portion of the container adjacent to 120 said edge parallel to the container axis, and means for moving said pressure device radially with respect to said container.

8. In an apparatus of the kind described, 125 the combination with a support, of mechanism for supporting a metal container, an abutment member adapted to engage one face of said container near one edge thereof, a movable pressure device for exerting pressure against the other face of said container said support being adjustable to accommodate containers of different heights.

7. In an apparatus of the kind described, the combination with a support, of mechanism for clamping a metal container to prevent longitudinal movement thereof, means for rotating said container about its axis, a platform on said support, a carrier pivoted on said support eccentrically of the container axis, an abutment roller pivoted about a vertical axis on said carrier and adapted to engage one face of the container near one rim thereof, a pressure device on said platform for exerting pressure against the other face of the container and spaced from said roller in the direction of the container axis by a distance approximately equal to the thickness of the container shell, means for moving said pressure device radially relatively to said container, and an arm connected to said carrier and adapted to swing said abutment roller about said eccentric pivot, into engagement with and away from said container.

8. In an apparatus of the kind described, the combination with a support, of mechanism for clamping a metal container to prevent longitudinal movement thereof, means for rotating said container about its axis, a platform on said support, an abutment member mounted on said platform and adapted to engage one face of said container near one rim thereof, a ring rotatably mounted in the plane of said abutment member and adapted to engage the said other face of said container, a pressure device on said platform for exerting pressure against the other face of the container at a point adjacent to said abutment, and means for moving said pressure device radially with respect to said container.

9. In an apparatus of the kind described, the combination with a support, of mechanism for clamping a metal container to prevent longitudinal movement thereof, means for rotating said container about its axis, a platform on said support, a carrier pivoted on said support eccentrically of the container axis, an abutment roller pivoted about a vertical axis on said carrier and adapted to engage one face of said container near one rim thereof, a ring, horizontally and vertically mounted guiding rollers for rotatably supporting and guiding said ring in the plane of said abutment roller, said ring being adapted to engage the other face of the container, a pressure device on said platform for exerting pressure against the other face of the container at a point spaced vertically from said abutment roller by a distance equal to the thickness of the container shell, means for moving said pressure device radially relatively to said container, and an arm connected to said carrier and adapted to swing said abutment roller, about said eccentric pivot, into engagement with and away from said container.

10. In an apparatus of the kind described, the combination with a support of mechanism

for clamping a metal container to prevent longitudinal movement thereof, means for rotating said container about its axis, a platform on said support, an abutment member mounted on said platform and adapted to engage one face of the container near one edge thereof, a pressure device on said platform for exerting pressure against the other face of said container from its edge to a point on the container adjacent to said abutment, and situated between said edge and said abutment, said device including a block slidably mounted on said platform and a roller carried by said block, means cooperable with said roller to hold the portion of the container adjacent to said edge parallel to the container axis, and means for moving said block radially with respect to said container.

11. In an apparatus of the kind described the combination with a support, of mechanism for clamping a metal container to prevent longitudinal movement thereof, means for rotating said container about its axis, a platform on said support, an abutment member mounted on said platform and adapted to engage one face of the container near one rim thereof, a pressure device on said platform for exerting pressure against the other face of the container at a point adjacent to said abutment, said device including a block slidably mounted on said platform, a roller carried by said platform and adapted to engage the said other face of the container, a second roller carried by said block and adapted to engage the first mentioned face of the container, and means for moving said block radially with respect to said container.

12. In an apparatus of the kind described, the combination with a support, of mechanism for clamping a metal container to prevent longitudinal movement thereof, means for rotating said container about its axis, a platform on said support, an abutment member mounted on said platform and adapted to engage one face of the container near one rim thereof, a pressure device on said platform for exerting pressure against the other face of the container at a point adjacent to said abutment, said device including a block slidably mounted on said platform, a roller carried by said platform and adapted to engage the said other face of the container, a second roller carried by said block and adapted to engage the first mentioned face of the container, a resilient connection between said rollers for urging the second roller toward the first, and means for moving said block radially with respect to said container.

13. In an apparatus of the kind described, the combination with a support, of mechanism for clamping a metal container to prevent longitudinal movement thereof, means for rotating said container about its axis, a platform on said support, an abutment member mounted on said platform and adapted to

engage one face of said container near one rim thereof, a pressure device on said platform for exerting pressure against the other face of said container at a point adjacent to said abutment, means for moving said pressure device radially with respect to said container, and an element movable with said pressure device and cooperating therewith to retain the free end of the container parallel with the main body of the container during the flanging of the latter.

14. The method of flanging cylindrical metal containers which comprises holding a container against radial movement at one face thereof at a point spaced from the edge thereof, exerting pressure by means of a pressure device against the opposite face of said container along a line from its edge to a point on the container adjacent said first named point disposed between said edge and said first named point, producing relative rotation between the said pressure device and the container, and simultaneously holding the end portion of the container adjacent to such edge parallel to the container axis.

15. The method of flanging cylindrical metallic containers which comprises holding a container against radial movement at one face thereof at a point spaced from the edge thereof, rotating said container about its axis, exerting pressure against the opposite face of said container along a line from its edge to a point on the container adjacent said first named point and disposed between said edge and said first named point, and simultaneously holding the end portion of the container adjacent to such edge parallel to the container axis.

16. The method of flanging cylindrical metallic containers which comprises clamping a container against longitudinal movement, holding the same against radial movement in one direction at a point spaced from an edge thereof, rotating said container about its axis, exerting pressure in said direction against the container along a line extending from said edge of the container to a point between said edge and said first mentioned point and spaced from said first mentioned point a distance along the length of the container approximately equal to the thickness of the container shell, and simultaneously holding the end portion of the container adjacent to such edge parallel to the container axis.

FERDINAND BRAUN,
